BED ATTACHMENT

Madge B. Miskimen, Indianapolis, Ind.

Application March 28, 1951, Serial No. 218,020

10 Claims. (Cl. 5—319)

1

This invention relates to bed attachments, and has particular reference to an adjustable support for the bedclothes at the foot of the bed to relieve the occupant's feet from the weight thereof, thus contributing to the comfort of the occupant, particularly in cases of foot injuries.

Numerous efforts have been made to provide a suitable support for bedclothes, but either the supports heretofore contrived are rigid attachments to a bed structure, such as the frame or spring, and hence, may not be readily disposed of when making up the bed or when the bed is occupied by one not requiring the use of the attachment, or the devices have been large, cumbersome and obtrusive.

In accordance with the present invention, an attachment for beds is provided which is simple in construction, effective in use for supporting bedclothes, and folds out of the way and out of sight when not in use, so as to enable the bed to be made up without interference by the apparent presence of the device.

In a preferred embodiment of the invention, a longitudinal support for vertical arms is provided which extends under the mattress at the location of the occupant's feet, is extensible longitudinally to accommodate the width of the mattress, and also holds the arms frictionally against the corresponding opposite edges of the mattress whereby the arms may be adjusted to any angle above the surface of the mattress. The upper or free ends of the arms are connected by a tape, preferably an elastic tape, for supporting the bedclothes above the mattress.

It will be seen that the bed attachment of this invention may be readily and quickly emplaced under the mattress without requiring any attachment to the frame or spring of the bed and nevertheless is held firmly in adjusted position by frictional contact of the side arms with the edges of the mattress so that the elevation of the bedclothes by the supporting tape may be adjusted by regulating the angle of the side arms. When the bed is not in use, the side arms are simply folded down alongside the corresponding edges of the mattress either toward the head or the foot of the bed, so that the tape lies flatwise on the surface of the mattress sheet.

For a more complete understanding of the invention, reference may be had to the accompanying drawings, in which:

Figure 1 is a front elevation of the bed attachment of this invention shown emplaced beneath a mattress; and

Fig. 2 is a perspective thereof showing its rela-

2

tion to the mattress while performing its bedclothes-lifting function.

Referring to the drawings, numerals 10 and 11 designate a pair of coil springs held relatively rigid laterally by internal rods 12 and 13 having transverse holes 14 near their outer ends secured to the outer ends of the corresponding springs in which is inserted the inwardly turned outer ends 15 of the springs 10 and 11.

10 The inner ends of the springs 10 and 11 are shaped to provide eyes 16 and 17 which are linked by a flexible inextensible member such as a link chain 18, whereby the device may be folded upon itself to reduce the space it occupies when packaged or in storage.

The outer ends of the rods 12 and 13 are turned at right angles to each other to provide the corresponding lateral extensions 19 and 20 which serve as pins to be inserted in corresponding longitudinal sockets 21 and 22 formed in the ends of the parallel side arms 23 and 24 and preferably slightly tapered so as to grip the extensions 19 and 20, which may be tapered, alternatively.

25 Side arms 23 and 24 are preferably made of a suitable material such as wood, a phenolic resin, an initially plastic material, such as methyl methacrylate, vinyl acetate or chloride or a mixture thereof, or the like. The length of the side arms 23 and 24 depends somewhat on the height to which the bedclothes are to be elevated above the mattress, and upon the thickness of the mattress, but usually the total length of the side arms need not materially exceed sixteen inches.

30 Adapted to extend between the free ends of the side arms 23 and 24 to support the bedclothes is a suitable flexible tape 25, preferably elastic, so as to extend tautly between the side arms 23 and 24 so as to adequately support the bedclothes resting thereon. Conveniently, tape 25 is provided with take-up clips 26 whereby to adjust the length of the tape 25.

35 So that the tape 25 may be readily detached for disassembly, cleansing and the like, the ends of the tape 25 are provided with metal loops 27 which fit over corresponding pins 28 set into the free ends of the side arms 23 and 24, preferably within a recess 29, so that the pins 28 and the loops 27 do not form obstructions on which the bedclothes can catch while adjusting the angle of the arms 23 and 24.

40 In use of the bed attachment of this invention, it is first assembled by axially aligning the two spring portions 10 and 11 about the chain 18 to the position shown in Fig. 1, and the aligned 45 spring portions 10 and 11 placed underneath the

50 55

mattress M near the foot thereof approximately beneath the normal position of the occupant's feet, as shown in Fig. 2.

The angular extensions 19 and 20 are pulled apart so as to overlap the sides of the mattress as shown in Fig. 2 which requires stretching the springs 10 and 11 to the corresponding degree. Then the side pieces 23 and 24 are placed over the corresponding pins 19 and 20, with the flat surfaces of the side arms 23 and 24 frictionally engaging the sides of the mattress and to a degree depending upon the tension of springs 10 and 11.

After the side arms 23 and 24 have been placed in the position in the manner described, the end loops 27 of tape 25 are slipped over the corresponding pins 28 and then the side arms may be folded to a substantially horizontal position with the tape 25 lying flatwise upon the upper surface of the mattress, i. e., upon the bottom sheet. The bed is then made in the usual way, after which the side arms 23 and 24 and the tape 25 will not be visible under the bedclothes.

When the device is to be placed in use, the side arms 23 and 24 are moved upwardly about 25 the axis of the corresponding rods 12 and 13 to an angle determined by the height that it is desired to raise the bedclothes above the mattress. By reason of the friction with which the side arms 23 and 24 are held against the sides of the mattress, the side arms 23 and 24 will remain in any angular position to which they have been moved.

Usually it is desired to relieve both feet of the weight of the bedclothes, so that arms 23 and 24 are normally moved to the same angle. However, on occasion, only one side of the bedclothes is required to be elevated, and in that event, one of the side arms 23 or 24 is moved to a higher angle than the other, a condition which is afforded by the chain 18 enabling relative angular movement between the springs 10 and 11, as will be readily understood.

Although a preferred embodiment of the invention has been illustrated and described herein, it is to be understood that the invention is not to be limited thereto, except by the scope of the appended claims.

I claim:

1. In a bedclothes lifting attachment for a bed including a mattress, the combination of an elongated member adapted to transversely underlie the mattress and to be held in place thereby, lateral side arms extending upwardly from the free ends of said member to be located at opposite sides of the mattress, and a flexible bedclothes-supporting element extending between the free ends of the side arms and adapted to extend across the mattress to support the bedclothes in spaced relation to the mattress.

2. In a bedclothes lifting attachment for a bed including a mattress, the combination of an elongated member adapted to transversely underlie the mattress and to be held in place thereby, lateral side arms extending upwardly from the free ends of said member to be located at opposite sides of the mattress, a flexible bedclothes-supporting element extending between the free ends of the side arms for supporting the bedclothes in spaced relation to the mattress, and a lost motion connection in said elongated member affording relative angular movement between the side arms.

3. In a bedclothes lifting attachment for a bed including a mattress, the combination of

an elongated member adapted to transversely underlie the mattress and to be held in place thereby, lateral side arms extending upwardly from the free ends of said member to be located at opposite sides of the mattress, a flexible bedclothes-supporting element extending between the free ends of the side arms and adapted to span the mattress and support the bedclothes in spaced relation to the mattress, and tension means in said elongated member drawing the side arms frictionally against the corresponding sides of the mattress.

4. In a bedclothes lifting attachment for a bed including a mattress, the combination of an elongated coil spring adapted to transversely underlie the mattress and be held in place thereby, lateral side arms extending upwardly from the free ends of said coil spring to be located at opposite sides of the mattress, and a flexible bedclothes-supporting element extending between the free ends of the side arms and adapted to extend across the mattress and support the bedclothes in spaced relation to the mattress.

5. In a bedclothes lifting attachment for a bed including a mattress, the combination of an elongated coil spring adapted to transversely underlie the mattress and be held in place thereby, lateral side arms extending upwardly from the free ends of said coil spring to be located at opposite sides of the mattress, and a flexible bedclothes-supporting element extending between the free ends of the side arms and adapted to extend across the mattress and support the bedclothes in spaced relation to the mattress.

6. In a bedclothes lifting attachment for a bed including a mattress, the combination of a pair of coil springs connected together to form an elongated member adapted to underlie the mattress, lateral side arms extending upwardly from the free ends of said member to be located at opposite sides of the mattress, and a flexible bedclothes-supporting element extending between the free ends of the side arms and adapted to extend across the mattress and support the bedclothes in spaced relation to the mattress.

7. In a bedclothes lifting attachment for a bed including a mattress, the combination of an elongated coil spring adapted to transversely underlie the mattress, rods projecting from the opposite free ends of said spring and secured thereto, upward extensions on the projecting rods to be located at opposite sides of the mattress, and a flexible bedclothes-supporting element extending between the free ends of the extensions to support the bedclothes in spaced relation to the mattress.

8. In a bedclothes lifting attachment for a bed including a mattress, the combination of a pair of coil springs, a rod projecting from one end of each spring and secured thereto, a flexible connection between the other ends of said springs to form an elongated member adapted to underlie the mattress and be held in place thereby, upward extensions on the projecting rods to be located at opposite sides of the mattress, and a flexible bedclothes-supporting element extending between the free ends of the extensions to support the bedclothes in spaced relation to the mattress.

9. In a bedclothes lifting attachment for a bed including a mattress, the combination of an elongated member adapted to underlie the mattress and be held in place thereby, lateral pins extending upwardly from the free ends of said member to be located at opposite sides of the

mattress, side arms having end sockets for removably receiving the corresponding lateral pins, and a flexible bedclothes-supporting element extending between the free ends of the side arms and adapted to extend across the mattress and support the bedclothes in spaced relation to the mattress.

10. In a bedclothes lifting attachment for a bed including a mattress, the combination of a pair of coil springs, a rod projecting from one end of each spring and secured thereto, a flexible connection between the other ends of said springs to form an elongated member adapted to underlie the mattress and be held in place thereby, upward extensions on the projecting rods at op- 15

posite sides of the mattress, side arms having end sockets for removably receiving the corresponding upward extensions, and a flexible bedclothes-supporting element extending between the free ends of the side arms and adapted to extend across the mattress and support the bedclothes in spaced relation to the mattress.
